United States Patent

Des. 235,598
Patented July 1, 1975

235,598

SHAVE CREAM DISPENSER

Theodore R. Peterson, Hinsdale, Ill., assignor to
The Gillette Company

Filed Sept. 26, 1973, Ser. No. 400,933

Term of patent 14 years

Int. Cl. D9—01

U.S. Cl. D6—95

FIG. 3

FIG. 5

FIG. 2

FIG. 6

FIG. 1

FIG. 4

FIG. 1 is a view in front elevation of a shave cream dispenser showing my new design;

FIG. 2 is a view in side elevation;

FIG. 3 is a view in rear elevation;

FIG. 4 is a top plan view;

FIG. 5 is a bottom plan view; and

FIG. 6 is a view in section partly broken away along line 6—6 of FIG. 1.

I claim:

The ornamental design for a shave cream dispenser, as shown.
